UNITED STATES PATENT OFFICE.

CARSON J. SHELDON, OF ELYRIA, OHIO, ASSIGNOR OF TWENTY-FIVE PER CENT TO W. J. FITZGIBBON AND OF TWENTY-THREE PER CENT TO GEORGE L. SCHWARTZ, BOTH OF YOUNGSTOWN, OHIO.

BOWLING PIN.

Application filed May 7, 1926, Serial No. 107,436. Renewed July 26, 1928.

The present invention relates to improvements in bowling alley pins, such as ten pins and duck pins, and has reference more particularly to an improvement over the bowling pin disclosed in Patent No. 1,585,123, granted to me May 18, 1926.

One of the important objects of the present invention is to provide a bowling pin of the type disclosed in the aforementioned application wherein the inner ring is provided with means for permanently securing the same on the bottom of the pin against accidental displacement.

A further object is to provide a bowling pin wherein said ring is provided with means whereby an interlocking association between the rubber protector ring and said inner ring is provided.

A still further object is to provide a bowling pin of the above mentioned character which is simple in construction, inexpensive, strong, and durable and further well adapted to the purpose for which it is designed.

Other objects and advantages of the invention will become apparent during the course of the following description taken in connection with the accompanying drawing.

In the accompanying drawing forming a part of this application and in which like numerals designate like parts throughout the several views:

Figure 1 is a sectional view of the metallic and fiber rings which encircle the shank portion of the pin, and also showing the rubber protector ring, and the manner in which the prongs are clinched in the pin.

Figure 2 is a side elevation of the metallic ring and the fiber ring associated therewith.

Figure 3 is a vertical sectional view taken approximately on line 3—3 of Figure 2, and

Figure 4 is a transverse section through the upper portion of one of the prongs.

In the drawing wherein for the purpose of illustration is shown the preferred embodiment of my invention, the numeral 1 designates the bowling pin which is preferably formed of maple wood and may be either a ten pin or a duck pin. The lower end or base of the pin is under cut as illustrated at 2 and extending downwardly therefrom is the central shank portion 3. An annular groove 4 is formed in the under cut portion 2 and the same extends around the upper portion of the reduced shank 3 in the

manner as is clearly shown in Figure 1, and as is further set forth in my aforementioned Patent No. 1,585,123 granted to me May 18, 1926.

Adapted to fit over the shank 3 is the inner ring 5 which is formed of any suitable composite material preferably fiber. Cooperating with the fiber ring 5 is the metallic ring 6. These rings are of the same width and for the purpose of securing the same together, the metallic outer ring 6 is provided with the inwardly projecting protuberances 7, the same being adapted to fit in suitable openings 8 provided therefor in the fiber ring 5. This construction is more clearly shown in Figures 1 and 3 of the drawing. Any number of these protuberances and cooperating openings may be provided as is necessary for securing the two rings together.

Extending upwardly from the upper edge of the metallic outer ring 6, are the series of prongs 9. The upper portions of the prongs are bent along their longitudinal centers so that the upper portion of each prong is arched or substantially U-shaped in cross section as shown at 10 with reference to Figure 4 of the drawing. The upper end of each prong is furthermore beveled as illustrated at 11 so as to provide a relatively sharp edge on each prong to facilitate the driving of the prongs into the base of the pin and to further aid the prongs in being directed inwardly toward the center so as to become clinched in the pin in the manner clearly shown in Figure 1.

The provision of the prongs on the upper edge of the metallic ring 6 will provide a means whereby the rings will be properly secured around the shank 3 against accidental displacement from the pins.

Cooperating with the aforementioned ring is the outer protector ring 12 which is formed of rubber, and this ring is adapted to be vulcanized to the outer face of the metallic ring 6. The upper portion of the metallic ring 6 is further provided with the cut out portion 13 and these cut out portions form key ways for the adjacent portions of the rubber protector ring 12 whereby an interlocking association of the rubber protector ring with the metallic ring 6 is formed.

The rubber protector ring is provided with the downwardly beveled upper face 14

for cooperation with the undercut portion 2 of the pin 1, and this ring is further provided with the upwardly extending annular rib 15 on the inner portion of the beveled face 14 adjacent the inner edge of the rubber protector ring and this rib is adapted to be disposed with the annular groove 4 together with the upper portion of the fiber and metallic rings 5 and 6 respectively.

10 As the purpose and construction of the rubber protector ring is fully covered in my Patent No. 1,585,123 granted to me May 18, 1926, a further discussion thereof in this case is not thought necessary.

15 The provision of the prongs on the metallic ring 6 will securely hold the same in position on the bottom of the pin around the reduced shank 3 and there will be no possibility of any of the rings becoming disengaged from the bottom of the pin when the parts are once assembled.

20 While I have shown the preferred embodiment of the invention, it is to be understood that minor changes in the size, shape, and arrangement of parts may be resorted to without departing from the spirit of the invention and the scope of the appending claims.

Having thus described the invention, what 30 I claim as new and desire to secure by Letters Patent is:—

1. A bowling pin having a central reduced shank portion formed on the bottom thereof, a metallic ring encircling said shank, securing means for said ring, a rubber protector ring encircling the aforementioned metallic ring, said metallic ring being provided with cut out portions forming key ways for interlocking association with the rubber protector ring.

2. A bowling pin having a central reduced shank portion formed on the bottom thereof, a metallic ring encircling said shank, securing means for said ring, a rubber protector ring encircling the aforementioned metallic ring, said securing means comprising prongs extending upwardly from the metallic ring and adapted to be driven into the bottom of the bowling pin.

3. A bowling pin having a central reduced shank portion formed on the bottom thereof, a metallic ring encircling said shank, securing means for said ring, a rubber protector ring encircling the aforementioned metallic ring, said securing means comprising prongs extending upwardly from the metallic ring and adapted to be driven into the bottom of the bowling pin, the upper ends of the prongs being beveled to provide relatively sharp cutting edges whereby the prongs are disposed inwardly in clinching relation.

4. A bowling pin having a central reduced shank portion formed on the lower end thereof, a metallic ring encircling said shank, a rubber protector ring encircling the metallic

ring, and securing means for said metallic ring, said means comprising a series of prongs extending upwardly from the metallic ring, the upper portion of each prong being arched transversely, the upper edge of each prong being beveled to provide a relatively sharp cutting edge whereby the prongs may be driven into the bottom of the bowling pin so as to dispose the upper ends thereof inwardly in clinching relation.

5. A bowling pin having a central reduced shank portion formed on the lower end thereof, an inner composite ring encircling the shank, a metallic ring encircling the composite ring, means for securing said rings together, a rubber protector ring encircling the metallic ring, and means associated with the metallic ring for securing the same on the bottom of the bowling pin.

6. A bowling pin having a central reduced shank portion formed on the lower end thereof, an inner composite ring encircling the shank, a metallic ring encircling the composite ring, means for securing said rings together, a rubber protector ring encircling the metallic ring, means associated with the metallic ring for securing the same on the bottom of the bowling pin, said first mentioned means comprising a series of protuberances extending inwardly from the metallic ring, the composite ring being provided with openings for cooperation with the respective protuberances.

7. A bowling pin having a central reduced shank portion formed on the lower end thereof, an inner composite ring encircling the shank, a metallic ring encircling the composite ring, means for securing said rings together, a rubber protector ring encircling the metallic ring, means associated with the metallic ring for securing the same on the bottom of the bowling pin, said last mentioned securing means comprising a series of prongs extending upwardly from the upper edge of the metallic ring and adapted to be embedded in the bottom of the pin in clinching relation.

8. In a bowling pin construction of the class described, the combination with a bowling pin having a cutaway portion, of a protector ring fitted in the cutaway portion, and means for securing the ring in said cutaway portion by an interlocked connection with the pin and there maintaining it in proper position.

9. In a bowling pin construction of the class described, the combination with a pin of a plurality of rings around said pin including a protector ring and means for positively fastening said rings to the body of the pin by creating an interlocked connection with said last named means and the pin.

10. In a bowling pin construction of the class described, the combination with the body of a bowling pin, of a protector ring

therefor surrounding said pin, a composition ring interposed between the protector ring and the body of the pin and means for holding the composition ring and protector 5 ring in proper position.

11. In a bowling pin construction of the class described, the combination with the body of a bowling pin, of a protector ring therefor surrounding said pin, a composition 10 ring interposed between the protector ring and the body of the pin and means for holding the composition ring and protector ring in proper position, said means comprising a member having interlocking relationship 15 with both the protector ring and the composition ring and including portion imbedded in the body of the pin.

12. A protector unit assembly adapted for use with bowling pins comprising, a combination, a composition ring, a rubber pro-

tector ring, a metallic ring intermediate the rings aforesaid, and means for fastening said assembly to a bowling pin in proper position.

13. A protector ring unit assembly adapted for use with bowling pins wherein they 25 are located in a cutaway portion thereof, comprising in combination, an outer protector ring having metallic retainer ring interlocked with the first named ring.

14. A protector ring unit assembly for 30 bowling pins, comprising, in combination, an outer protector ring, an inner composition ring and a retaining ring intermediate said outer and inner ring including members adapted to project into the body of a bowl- 35 ing pin whereby the unit assembly is positively held in proper position with respect to the pin.

In testimony whereof I affix my signature.
CARSON J. SHELDON.
